BASE FOR STANDS

Harold Borghesi, Union City, N. J.

Application March 29, 1947, Serial No. 738,160

3 Claims. (Cl. 248—194)

1

This invention relates to bases for stands and refers more particularly to bases for lamp stands, display stands or similar columns or elongated articles maintained in an upright position.

An object of the present invention is the provision of a base for a vertical lamp or display stand which is inexpensive to manufacture and durable and effective in use.

Another object is the provision of a base of the described type which can be effectively used to support a substantial load which will maintain a stand or column in an upright position without danger of collapsing or tipping over.

A further object is the provision of a base which is composed of a small number of parts so that it can be quickly and easily assembled and attached to the upright stand or column.

Other objects of the present invention will become apparent in the course of the following specification.

The objects of the present invention may be realized through the provision of a base which includes a shell filled with a suitable weight such as concrete or cement. The shell may consist of an upper and lower portion adapted to interengage by means of an annular groove. The lower shell portion has suitable rib-like legs pressed radially out of the shell. The shell operates with a stand holder having the shape of a nut extending through the shell and carrying the threaded lower end of the stand or column. The nut has a lower flange which is bent over the edge of the shell to provide a secure connection.

The invention will appear more clearly from the following detailed description when taken in connection with the accompanying drawing showing by way of example a preferred embodiment of the inventive idea.

In the drawing:

Figure 1 is a bottom view of a base constructed in accordance with the principles of the present invention.

Figure 2 is a section along the line 2—2 of Figure 1.

Figure 3 shows a part of the base in section on a larger scale; and

Figure 4 is a section showing part of a lower shell portion, with the filler broken away, constructed in accordance with a modified form of the invention.

The base shown in the drawing has a lower shell portion 10 and an upper shell portion 11. The lower shell portion 10 has a bottom 12 and an annular side wall 13 provided with an in-

2

wardly directed groove 14 which is located close to the upper edge 15 of the wall. The bottom 12 has a central opening 16. Furthermore, the bottom 12 is provided with radial ribs 17 which are pressed out of the material of the shell and which terminate in round legs or supporting elements 18.

The upper shell portion 11 has a small opening 20 in its top wall 19 located directly above the opening 16. Furthermore, the upper shell portion 11 is provided with a depending annular skirt or side wall 21 which is substantially of the same height as the side wall 13 of the lower shell portion 10. The skirt 21 has a groove 22 which fits into the groove 14 so that when the shell portion 11 is placed over the shell portion 10 a firm connection may be established between these two members to form a single casing which may be conveniently filled by any suitable material 23 such as concrete, cement or a plastic mass.

The column or stand 24a is supported in the described base 10, 11 by means of an elongated nut 24 which is so dimensioned that it extends essentially between the openings 16 and 20. The bottom of the nut 24 has a shoulder 25 resting upon the inner edge of the opening 16. The top surface 26 of the nut 24 rests upon the inner edge of the opening 20. A flange 27 extends through the opening 16 and is bent outwardly over the edges of the opening to provide a firm connection between the shell 10, 11 and the nut. The nut 24 is provided with inner screw threads 28 and the stand 24a has a threaded end 29 which is screwed into the nut 24, thus establishing a secure connection between the base and the stand.

As shown in Figure 4, side wall 13 of lower shell portion 10 may be crimped as at 30, the crimping extending around side wall 13 from a point intermediate the ends to the upper end thereof. In this construction groove 14 may be dispensed with since the crimping serves to retain the filler 23 within the lower shell portion. An upper shell portion 32 may be also crimped so as to mesh with crimping 30 as shown in Figure 4, or uncrimped as desired. In both instances upper shell portion 32 is retained on the lower shell portion by reason of a tight fit therewith.

The described base is quite inexpensive in manufacture and most sturdy and effective in use. It can carry heavy weights and be subjected to considerable forces without tipping over.

It is apparent that the example shown above has been given solely by way of illustration and not by way of limitation and that the illustration

above described is subject to wide variations and modifications without departing from the scope or intent of the present invention. All such variations and modifications are to be included within the scope of the present invention.

What is claimed is:

1. A base for stands and the like, said base comprising an upper shell member, a lower shell member engaging said upper shell member, said shell members having central openings formed therein, and a nut member centrally located in said shell members and having its lower end abutting the inner edge of the opening in said lower member, said nut member having a flange at its lower end embracing the outer edges of said opening. 15

2. A base for stands and the like, said base comprising an upper shell member, a lower shell member engaging said upper shell member, said shell members having central openings formed therein, and a nut member centrally located in said shell members and having its lower end against the inner edge of the opening in said lower member, said nut member having a flange at its lower end embracing the outer edges of

said opening, said nut member having an upper surface engaging the edge of said central opening of the upper shell portion.

3. A base for stands and the like, said base comprising a lower shell member having a central opening formed therein, and a nut member centrally located in said shell member and having a lower flange embracing the edges of said opening, said shell member having a side wall with a plurality of crimps formed therein extending from a point intermediate the bottom and top of said side wall to the top thereof.

HAROLD BORGHESSI.
